(57) **CLAIM**

An ornamental design for an applicator for artificial eyelash extensions as shown and described.

DESCRIPTION

FIG. 1 is an illustration of a front perspective view of an applicator for artificial eyelash extensions;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top view thereof;

FIG. 7 is a bottom view thereof; and,

FIG. 8 is a bottom perspective view thereof.

None of the broken lines form any part of the claimed invention.

1 Claim, 5 Drawing Sheets

Related U.S. Application Data

which is a continuation of application No. PCT/US2017/044217, filed on Jul. 27, 2017, said application No. 29/667,344 is a continuation-in-part of application No. 15/968,453, filed on May 1, 2018, now Pat. No. 10,638,826, which is a continuation of application No. PCT/US2017/067513, filed on Dec. 20, 2017.
